FIG 1

FIG 2

MARCEL BOUCHER
INVENTOR
BY Ben Casper
ATTORNEY

UNITED STATES PATENT OFFICE

120,611

DESIGN FOR A PIN OR SIMILAR ARTICLE

Marcel Boucher, New York, N. Y.

Application April 11, 1940, Serial No. 91,595

Term of patent 3½ years

To all whom it may concern:

Be it known that I, Marcel Boucher, a citizen of the United States, residing in New York city, in the county of New York and State of New York, have invented a new, original, and ornamental Design for a Pin or Similar Article, of which the following is a specification, reference being had to the accompanying drawing, forming part thereof.

Fig. 1 is a front elevational view of a pin or similar article showing my design, and

Fig. 2 is an edge elevational view thereof.

I claim:

The ornamental design for a pin or similar article, substantially as shown.
